(57) **CLAIM**

An ornamental design for the vehicle window shade with static cling mount as shown and described.

DESCRIPTION

FIG. 1 is a front view of a vehicle window shade with static cling mount.

FIG. 2 is a rear view of the vehicle window shade shown in FIG. 1.

FIG. 3 is a left-side view of the vehicle window shade shown in FIG. 1.

FIG. 4 is a right-side view of the vehicle window shade shown in FIG. 1.

FIG. 5 is a top view of the vehicle window shade shown in FIG. 1; and,

FIG. 6 is a bottom view of the vehicle window shade shown in FIG. 1.

The dashed lines along the periphery depict stitching and form no part of the design. The diagonal shade lines depict a transparent surface.

1 Claim, 6 Drawing Sheets
